ICE CRACKER

John S. Bradley, New York, N. Y., and John W. Dyer, South Orange, N. J.

Application September 23, 1931, Serial No. 564,530

2 Claims. (Cl. 83—63)

This invention relates generally to devices for cracking ice, and in particular ice cubes, such as are manufactured in modern household mechanical refrigerators.

Present day mechanical refrigerators for household use are equipped with a compartment within the freezing coils in which a series of pans, divided into rectangular compartments, for making cubes of ice, are located. For cooling ice water and some other beverages the whole cubes are satisfactory, but for making certain beverages, particularly those which are shaken, the whole cubes are too large and may be much more satisfactorily and successfully employed if they are cracked in several smaller pieces without being pulverized.

Previous devices of this general character have been, in effect, grinders which, in various ways, grind up the ice or in the nature of shavers which chip a thin layer from the surface. All of these forms reduce the ice to a substantially pulverized state. For many purposes, particularly shaker drinks, the ice should not be so finely ground because it melts too rapidly diluting the beverage and, for the same reason, failing to function effectively as one of the chief agents in thoroughly mixing and aerating it.

One of the major novel results which our invention has attained is the cracking of ice cubes into chunks substantially all of which are of appreciable size as compared with the snow and thin chips to which the ice is reduced by other devices, such as grinders and shavers. We have observed that ice and an ice cube in particular when subjected to a crushing pressure, as distinguished from a grinding or shaving action, resists the strain up to a certain critical point and then suddenly bursts asunder into chunks of the proper size and with the production of only a very minor amount of pieces small enough to be compared with those produced by grinding or shaving. Our invention is so designed that a heavy pressure may be applied to an ice cube with little effort to crack it as described above and in this it is to be distinguished from rotary and other devices which "chew up" or pick at the ice.

Two forms of our invention are illustrated by the accompanying drawing:

Figure 1 is a view in perspective partly broken away of one form of our invention;

Figure 2 is a view in perspective of another form.

Fig. 3 is a fragmentary sectional view of the cracking cylinder illustrating one manner in

which the cylinder may be mounted and in which the operating handle may be attached thereto; and

Fig. 4 is a fragmentary plan view of one form of cracking cylinder.

In the forms illustrated, our invention comprises a box-like body 1 composed of sides 2 and 3 and end 4. Top 5 and end 6 may be left open although, if desired, the top may also be closed and the end 6 provided with a hinged closure 6^a which can be opened by means of a handle 6^b to permit the insertion of an ice cube. Preferably the bottom 7 is open save for a series of slats or ribs 8 suitably spaced to support an ice cube. Preferably the upper surface of each rib 15 is in the form of an inverted V so that the ice cube will rest upon sharp edges, and it is also desirable that the ribs run in a fore-and-aft direction, as shown. However, these details are not essential.

In suitable bearings in sides 2 and 3 a crushing cylinder 11 is eccentrically mounted. It may be of any desired external contour. For example, it may be generally cylindrical as shown, a shape which may be inexpensively constructed. Preferably, its surface is formed into sections of alternate, large and smaller diameters 11^a and 11^b, respectively, having sloping sides to form, in effect, knife edges. It may also be cross cut longitudinally, if desired, so that the surface takes the form of a series of small pyramids.

Beyond the bearing at each end of the cylinder, and projecting outwardly from the sides 2 and 3, is a short stub 12 which may be square, hexagonal, fluted, or otherwise shaped to form a suitable operating connection between the crushing cylinder 11 and a handle 13. The handle 13 terminates in a fork 14, 15, at the ends of which holes or sockets are provided of suitable shape and size to operatively engage with stubs 12. Of course any other suitable form of connection between handle 13 and cylinder 11 may be employed. The design shown is simple, inexpensive and satisfactory and permits of adjustment of the handle 13 to the position most convenient for the cracking of ice cubes of any given thickness.

The exact size and location of cylinder 11 may be left to those skilled in the art. It should be of such a size and so positioned that when in the position shown in Fig. 1 the space between its under side and the ribs 8 is rather small and in any event substantially less than the thickness of an ice cube, whereas when in the position gained by rotating the handle 13 through 180 degrees, the space between the then under side of

the cylinder and the slats is somewhat greater than the thickness of an ice cube. By the term "thickness" we do not refer to any particular dimension, since it is immaterial whether the 5 ice cube is placed in the cracker upon its bottom, side or end.

The form of our device illustrated by Fig. 1 is also provided with a second handle 10 by means of which the cracker may be held over in any 10 convenient receptacle. In the form shown in Fig. 2 the cracker is provided with legs 16 and 17 by means of which it may be mounted upon a base 18 or secured to a table and there is also included a tray 19 adapted to slide under the cracker between 15 the legs to receive the cracked ice.

The cracker operates as follows: Handle 13 is first swung from the position shown in the drawing to prepare the cracker for the reception of an ice cube by elevating cylinder 11 as much as necessary. An ice cube is then inserted and handle 13 is swung back towards its original position, which will also cause rotation of cylinder 11. Since cylinder 11 is eccentrically mounted, as described above, such rotation will cause its surface 25 to contact with the ice cube and, as the rotation continues to exert a constantly increasing pressure upon it until it cracks or, to be more accurately descriptive, bursts into a number of smaller chunks. In short, the cylinder is in the 30 nature of an elongated cam capable of producing great pressure with ease. The progressive character of the pressure thus produced, together with the knife edged or pyramidal contour of the cylinder and the ribs, will cause the ice to burst as 35 heretofore described, rather than to chip or crush. The ice when cracked will drop through the ribs into a suitable receptacle beneath, or if a solid bottom is employed it will, of course, remain within the cracker and may be removed by inverting the device.

Of course, the cracker must be made of suffi-

cient strength to withstand the considerable pressures developed. This will be understood and provided for by any one skilled in the art.

Our device is obviously susceptible of many modifications. For example, the top may be 5 closed, if desired, or the bottom may be solid. The crushing means may be of some other general shape than that shown and its surface may be smooth or provided with other sorts of irregularities and, of course, the device may be made of 10 sufficient size to accommodate more than a single ice cube. However, such modifications would not constitute departures from our invention. The 15 particular forms which we have shown and described are for purposes of illustration only, and not intended as limitations of the invention.

We claim:

1. A device for cracking ice cubes which consists of a receptacle having two sides, a surface for supporting an ice cube and an abutment adjacent one end of said surface and at substantially a right angle thereto for limiting the movement of the cube in that direction, a cracking element supported between the sides and having a cracking surface swingable simultaneously towards 20 said supporting surface and towards said abutment to crack a cube held therebetween.

2. A device for cracking ice cubes which consists of a receptacle having two sides, a surface for supporting an ice cube and an abutment adjacent 30 one end of said surface and at substantially a right angle thereto for limiting the movement of the cube in that direction, a cracking element having a substantially cylindrical cracking surface and swingably supported between said sides 35 upon an axis other than the normal axis of said cylindrical surface, and means for swinging said cylindrical surface simultaneously towards said supporting surface and said abutment.
